UNITED STATES PATENT OFFICE

2,482,005

COUPLER

Edmund P. Kinne, Alliance, Ohio, assignor to
American Steel Foundries, Chicago, Ill., a corporation of New Jersey

Application July 16, 1943, Serial No. 494,945

10 Claims. (Cl. 213—159)

1

My invention relates to couplers and more particularly to an improvement on the design of coupler illustrated in my Patent No. 2,183,501, issued December 12, 1939, by the United States Patent Office. While the invention as illustrated herein is applied to the type of coupler shown and described in said patent, it will be understood that the present invention may with some modification be adapted to other couplers such as, for example, the E coupler, adopted as a standard by the Association of American Railroads.

The principal object of this invention is to provide means for holding the lock in locked position, which means will not be affected by the forces and the conditions which cause the anticreep of present couplers to release, thus failing to prevent the lock from raising to cause an accidental uncoupling. My novel anticreep means is supplemental to the anticreep presently utilized and the forces of gravity which are depended upon to cause the present anticreep to function.

A specific object of my invention is to provide means in the form of a spring which supplements the present anticreep means. The spring is effective to prevent creeping of the lock in the event that the usual anticreep means fails for some reason; however, the customary anticreep means is provided and functions as usual in the event that the spring for some reason should become inoperative.

A different object of my invention is to provide a novel wedge engagement between the knuckle tail and the lock, whereby as the latter is urged to locked position, it facilitates the closing of the knuckle.

In the drawings, Figure 1 is a horizontal sectional view through a coupler embodying my invention substantially as indicated by the line 1—1 of Figure 2, the parts operable within the coupler being shown in plan view with a portion of the knuckle tail broken away to illustrate the knuckle thrower therebeneath.

Figure 2 is a sectional view through the coupler head taken in the vertical plane indicated by the line 2—2 of Figure 1 with the lock and the parts associated therewith shown in elevation, a part of the lock being broken away.

Figure 3 is a view comparable to that of Figure 2 with the lock illustrated in its highest position riding on the open knuckle tail.

Figure 4 is a sectional view comparable to those of Figures 2 and 3 but illustrating the lock falling to locked position, and Figure 5 is a sectional view taken in the vertical plane indicated by the line 5—5 of Figure 4.

2

Figure 6 is a fragmentary sectional view taken in the vertical plane indicated by the line 6—6 of Figure 1.

Figure 7 is a fragmentary sectional view comparable to those of Figures 2 to 4 inclusive but illustrating the manner in which my novel anticreep or booster spring is applied within the coupler head.

Figures 8 and 9 illustrate in detail my novel 10 anticreep spring, Figure 8 being a side elevation thereof and Figure 9 being a top plan view thereof.

Describing my invention in detail, the coupler head, generally designated 2, is integrally formed with a shank 4, a fragmentary portion of which 15 is illustrated. A knuckle 6 is pivoted at 8 (Figure 1) for automatic action within the coupler head, as described in the above-mentioned patent, and a lock, generally designated 10, is pivoted within the head 2 by the spaced trunnions 12 and

20 14, the trunnion 12 being received within a complementary opening in the adjacent coupler head wall, and the trunnion 14 being received within a trunnion pocket integrally formed within the coupler head.

25 The lock 10 comprises the anticreep lug 16 for engagement with the anticreep stop or lug 18 of the lifter, generally designated 20, said lifter being operable by means of a rotor 22 received within an opening 24 therethrough and keyed within

30 said opening by means of a key 26 received within a complementary slot 28 partially defining said opening. The rotor is pivoted on the axis 30 by means of spaced trunnions thereon at opposite sides of the key 26, as described in detail in the 35 above-mentioned patent. It will be understood that the rotor is rotated on its axis 30 by means of a conventional operating rod, whereby the lifter 20 is rotated to operate the lock and the knuckle thrower as hereinafter discussed.

40 The lifter 20 comprises an abutment face 32 for engagement with the cam surface 34 on the lock, the lower end of said cam surface terminating in a lockset shoulder 36 for engagement with the lockset lug 38 of the lifter whereby the lock 45 is maintained in lockset position during an uncoupling operation. It will also be understood that after the lock has been rotated to its highest position, as illustrated in Figure 3, the face 32 of the lifter engages the operating arm 49 (Figure 1) of the knuckle thrower 42, said knuckle thrower being pivoted at 46 by means of a trunnion portion engaged with a complementary pocket formed in the coupler head. The knuckle arm 46 of the thrower is adapted for engagement with

55 the knuckle thrower pad 48 on the knuckle for

rotation of the same to open position as the face 32 of the lifter engages the operating arm 40 of the knuckle thrower to rotate the same in a counterclockwise direction, as seen in Figure 1, about its trunnion 44.

In locked position, as illustrated in Figure 1, the lock 10 is engaged at 50 with the locking face of the knuckle tail 52 and said lock is engaged at 54, 54 with the wall 56 of the coupler head, the lock being formed with a pulling lug 58 for engagement at 60 with the lug 62 formed on said wall 56, whereby the lock is prevented from creeping forwardly within the coupler under pulling service conditions.

The above-described coupler parts are substantially identical with those shown and described in my above-mentioned patent, and it will be understood that these parts are assembled and are maintained in assembled relationship in substantially the manner set forth in said patent. It may be noted that substantially the entire mass of the lock 10 is disposed forwardly of its trunnions 12 and 14 in order to facilitate its movement in dropping to locked position, and the present invention consists in combining with the above-described structure a torsion or booster spring, generally designated 64 and shown in detail in Figures 8 and 9, this spring being operable to resist raising of the lock from its locked position, as herein-after more fully described.

The spring, as illustrated in detail in Figures 8 and 9, consists of two coils 66 and 68 formed at their adjacent ends with a loop 70 for engagement at 72 (Figure 2) with the arcuate spring seat 74 formed on the upper surface of the lock. At their remote ends the coils 66 and 68 are formed with hooks 76 and 78 for engagement at 80 and 82, respectively, within notches formed in the rib 84 integrally joined with the coupler head. The engagement of the hooks 76 and 78 with the rib 84 will be best understood by a comparison of Figure 6 with any of Figures 2 to 4 inclusive. The coils 66 and 68 are received beneath a bridge-like retaining member 86 integrally formed with the coupler head and slotted as at 81 (Figure 1) to accommodate movement of the spring 64 as the lock is raised and lowered within the coupler head.

In assembling the spring 64, as illustrated in Figure 7, the coils are slipped beneath the retaining member 86 and are moved toward the rib 84 with the loop 70 of the spring, inclined downwardly as illustrated in this figure. When the hooks are in proper position within the notches 80 and 82, the loop may be raised for engagement with the lock as it is inserted through the front opening 88 in the coupler head, as described in detail in my above-mentioned patent. The opening 88 is best seen in Figures 2 to 4 inclusive.

Figure 3 illustrates the lock 10 in its highest position, riding on the knuckle tail 52 after the knuckle has been thrown open preparatory to a coupling operation. The lifter is illustrated in released position, to which it normally rotates in a counterclockwise direction, as illustrated in this figure, this rotation being caused by the counterweight portion 89 of the lifter which, after actuation thereof in a clockwise direction by means of the rotor, is operable to return the lifter to its released position as illustrated in each of Figures 2 to 4 inclusive. As illustrated in Figure 3, it will be seen that the coils of the anticreep spring 64 are placed under considerable torsion, whereby as the lock commences to drop

to locked position as illustrated in Figure 4, the spring 64 is exerting a considerable pressure to facilitate this action. Inasmuch as the knuckle tail, as clearly illustrated in Figure 5, is formed with a wedge surface 90 for engagement with the lock, it will be understood that the spring is operable to assist in moving the knuckle to closed position, whereupon the lock drops to locked position, as illustrated in Figures 1 and 2, between the locking face of the knuckle tail and the locking surface of the wall 56 of the coupler head. I have actually ascertained by experiment that the spring 64 is of considerable assistance in thus completing the final closure of the knuckle.

Figure 2 illustrates the lock in locked position but slightly raised from the seat 92 which the lock normally engages in this position. This figure shows the action of the spring 64 in resisting movement of the lock upward from the seat 92, thus supplementing the anticreep obtained as a result of the engagement of the anticreep lug 16 on the lock with the anticreep lug 18 on the lifter. In this connection it will be understood, as more fully described in my above-mentioned patent, that movement of the lock from the position illustrated in Figure 4 to that illustrated in Figure 2 results in a clockwise rotation of the lifter 20 as the lug 16 rides over the lug 18 on the lifter. When the lug 16 has passed the lug 18, the lifter, because of the counterweight portion 89 thereof, rotates in a counterclockwise direction to its released position, whereby the lugs 16 and 18 engage each other, as illustrated in Figure 2, to afford an anticreep.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a car coupler, the combination of a coupler head, a knuckle, a lock, a lifter, a rotor, and a knuckle thrower operable in said head, said knuckle thrower having an operating arm, said lifter having cam means adjacent its forward end and being rotatable to raise said lock by engagement of said means with the forward end of said lock and said lifter being further rotatable to engage said arm and operate said knuckle thrower for movement of said knuckle, said lock having trunnion means at its rear end substantially the entire mass of said lock being disposed upwardly of said trunnion means in lockset position, whereby the impact of coupling imparts a maximum falling impulse to rotate said lock from lockset position to normal locked position, the tail of said knuckle having a wedge surface 60 for engagement with the adjacent portion of said lock as the latter moves to locked position, and resilient means bearing against a portion of said coupler head and against said lock to facilitate the movement thereof to locked position, said resilient means being in the form of a torsion spring having a coil intermediate its ends, said spring being interlocked at one end thereof with means on said coupler head and said spring being in abutment at its opposite end with said lock, a retaining member formed within said coupler head and overlying said coil, and a rib within said coupler head and engaged with one end of said spring, the opposite end of said spring bearing against said lock.

2. In a car coupler, the combination of a cou-

pler head, a knuckle, a lock, a lifter, a rotor, and a knuckle thrower operable in said head, said knuckle thrower having an operating arm, said lifter having cam means adjacent its forward end and being rotatable to raise said lock by engagement of said means with the forward end of said lock and said lifter being further rotatable to engage said arm and operate said knuckle and thrower for movement of said knuckle, said lock having trunnion means at its rear end, substantially the entire mass of said lock being disposed upwardly of said trunnion means in lockset position, whereby the impact of coupling imparts a maximum falling impulse to rotate said lock from lockset position to normal locked position, the tail of said knuckle having a wedge surface for engagement with the adjacent portion of said lock as the latter moves to locked position, and resilient means bearing against a portion of said coupler head and against said lock to facilitate the movement thereof to locked position, said resilient means being in the form of a torsion spring having a coil intermediate its ends, said spring being interlocked at one end thereof with means on said coupler head and said spring being in abutment at its opposite end with said lock.

3. In a car coupler, the combination of a coupler head, a knuckle pivoted therein, a lock operable therein, a lifter, a rotor, and a knuckle thrower having a knuckle engaging arm and an operating arm, a lockset shoulder and an anticreep lug on said lock, said lifter being operable to raise said lock to lockset position by cam engagement therewith wherein said lock is supported by abutment of said lifter against said shoulder, and said lifter being further operable to rotate said knuckle thrower to open said knuckle by engagement with said operating arm, said lifter having an anticreep stop integral therewith, said lug and said stop having abutment against each other when said parts are in locked position to prevent a creeping action of said lock, said lifter and said rotor being keyed together for rotary movement when assembled in operative position, a bridge-like retaining member and a rib adjacent thereto within said coupler head, and a torsion spring comprising a coil received beneath said retaining member, one end of said spring being interlocked with said rib and the opposite end of said spring bearing against an adjacent surface on said lock for resisting movement thereof from its locked position.

4. In a car coupler, the combination of a coupler head, a knuckle, a lock, a lifter, a rotor, and a knuckle thrower operable in said head, said knuckle thrower having an operating arm, said lifter having cam means adjacent its forward end and being rotatable to raise said lock by engagement of said means with the forward end of said lock and said lifter being further rotatable to engage said arm and operate said knuckle thrower for movement of said knuckle, said lock having trunnion means at its rear end, substantially the entire mass of said lock being disposed upwardly of said trunnion means in lockset position, whereby the impact of coupling imparts a maximum falling impulse to rotate said lock from lockset position to normal locked position, movement of said lock from lockset to normal locked position being effective to rotate said lifter and establish an anticreep between said lock and said lifter, and resilient means for resiliently maintaining said lock and said lifter in anticreep relationship, said resilient means being in the form of a torsion spring bearing at opposite ends thereof against

said head and said lock, said spring comprising a coil intermediate its ends, and fulcrum means for said spring in the form of a bridge-like member integrally formed with said head and overlying said coil.

5. In a car coupler, the combination of a coupler head, a knuckle pivoted therein, a lock operable therein, a lifter, a rotor, and a knuckle thrower having a knuckle engaging arm and an operating arm, a lockset shoulder and an anticreep lug on said lock, said lifter being operable to raise said lock to lockset position by cam engagement therewith wherein said lock is supported by abutment of said lifter against said shoulder, and said lifter being further operable to rotate said knuckle thrower to open said knuckle by engagement with said operating arm, said lifter having an anticreep stop integral therewith, said lug and said stop having abutment against each other when said parts are in locked position to prevent a creeping action of said lock, said lifter and said rotor being keyed together for rotary movement when assembled in operative position, and resilient means engaging said coupler head and said lock for resiliently maintaining said lug in abutment with said stop, said resilient means being in the form of an elongated member bearing at its opposite ends against abutment means on said lock and said head respectively, and an integral bridge member within said head bearing against said elongated member intermediate its ends to afford a fulcrum therefor.

6. In a car coupler, a coupler head, parts operable in said head comprising a lock having lockset means, a knuckle thrower, a rotor, a lifter mounted on said rotor, cooperating anticreep means on said lifter and said lock adjacent their rear ends, and cam means on the forward end of said lifter cooperable with the forward end of said lock to rotate said lock from locked to lockset position, wherein the forward end of said lifter is in abutment with said lockset means, resilient means bearing against said coupler and a portion of said lock to resist said rotation from locked position, said resilient means being in the form of a torsion spring interlocked at one end thereof with means in the coupler head, said spring slidably bearing at its opposite end against an arcuate seat on said lock, said spring comprising an intermediate coil, and an integral bridge member within said head overlying said coil and bearing thereagainst.

7. In a car coupler, a coupler head, a lock, a lifter, a rotor and a knuckle thrower operable therein, said lock having trunnions at its rear end and lockset means at an intermediate point, said lifter having cam means adjacent its forward end engageable with said lock remote from said trunnions and forwardly of said lockset means upon rotation of said lifter, said lock being operable on release from said lockset position to impart rotative movement to said lifter and establish an anticreep therewith, a torsion spring with an intermediate coil and spaced end portions engaging said coupler head and said lock respectively for yieldingly maintaining the latter in its anticreep relationship with respect to said lifter, and a retaining member within said head in fixed relation with respect thereto, said member being spaced from said trunnions and bearing against said coil to afford a fulcrum for said spring.

8. In a car coupler, a coupler head, a lock, a lifter, a rotor and a knuckle thrower operable therein, said lock having trunnions at its rear

end and lockset means at an intermediate point, said lifter having cam means adjacent its forward end engageable with said lock remote from said trunnions and forwardly of said lockset means upon rotation of said lifter, said lock being 5 operable on release from said lockset position to impart rotative movement to said lifter and establish an anticreep therewith, resilient means having its opposite ends respectively engaging said coupler head and said lock for yieldingly maintaining the latter in its anticreep relationship with respect to said lifter, and a bridge-like retaining member formed within said head and spaced from said trunnions, said member bearing 10 against said resilient means intermediate its ends to afford a fulcrum therefor.

9. In a coupler, a coupler head, a knuckle pivoted therein, a lock pivoted at the rear extremity thereof within said head and movable into and out of locking engagement with said knuckle, a 20 torsion spring bearing at opposite ends thereof respectively against a rib on said head and an upwardly facing surface on said lock, said spring comprising a coil intermediate its ends, and an integral bridge-like retaining member formed 25 within said head and overlying said coil, said

member being spaced rearwardly of said lock.

10. In a coupler, a coupler head, a knuckle pivoted therein, a lock movable into and out of locking engagement with said knuckle, an elongated resilient member bearing at opposite ends thereof respectively against said head and said lock, and an integral bridge-like retaining member formed within said head and bearing against said elongated member intermediate its ends to afford a fulcrum therefor.

EDMUND P. KINNE.
